UNITED STATES PATENT OFFICE.

VINCENT G. APPLE, OF DAYTON, OHIO.

ARMATURE.

Application filed May 20, 1918. Serial No. 235,688.

To all whom it may concern:

Be it known that I, VINCENT G. APPLE, a citizen of the United States, residing at Dayton, in the county of Montgomery and State of Ohio, have invented certain new and useful Improvements in Armatures, of which the following is a specification.

One of the objects of my invention is to provide a new and useful means of making 10 armatures, whereby to reduce the number of parts required; to render the structure more stable and efficient and to generally improve and accelerate the mode of construction.

Another and more specific object of my invention is to provide an improved means of 15 attaching commutator segments to the paired terminals of the armature conductors, whereby the inner and outer circumferential surfaces of the commutator may be used, 20 selectively or jointly, for contact with collecting brushes, thus providing a commutator having a greater capacity and a larger range of usefulness than when one surface only is available for the purpose.

Other, further and more specific objects of 25 my invention will become readily apparent, to persons skilled in the art, from a consideration of the following description when taken in conjunction with the drawings, 30 wherein:—

Fig. 1 shows a section of an armature with a commutator section being welded thereto.

Fig. 2 shows a view in direction of the arrows of line 2—2 of Fig. 1.

Fig. 3 is a similar view showing the collecting brushes applied on the outer and the inner surface of the commutator so constructed.

In all the views the same reference characters are employed to indicate similar parts.

In the selected embodiment 5 is a spider for supporting the core 6 of an armature. The conductors 7 and 8, having their ends welded together at 9, pass thru perforations or slots in the outer periphery of the core. 10 is a shaft upon which the spider 5 temporarily is mounted, being prevented from axial movement by a cap screw 11 which enters the shaft and which engages the hub 12 of the spider. A disc 13, preferably of metal, slidably fits an insulating sleeve 14 that is placed over the shaft 10, and is the means for concentrically spacing and temporarily supporting the armature terminals 9, in concentric alignment. A lateral projection 15, of the disc 13,

supports a commutator segment guide comprising an insulating ring 16. This ring is provided with radially disposed spaced-apart plates 17, to lie between the commutator sections 18 and for properly spacing the commutator sections apart in the process of welding them to the ends of the terminal 9, of the armature conductors. A disc 19 of insulating material prevents contact of the metal disc 13 with any of the metallic part of the armature structure except the conductors or terminals 9 at the inner surface thereof. A ring 20 overlies the outer surface of the terminals 9, and clamps them tightly to the outer peripheral surface of the disc 13, so as to bring them all into concentric arrangement, or alignment with the shaft 10, and to make electrical connection between the terminals and the ring 20. The disc 13 is electrically connected with the ring 20, by a wire 21. The diameter of the ring 20 is capable of being contracted by the perforate 75 radially projecting ears 22, thru which the bolt 24 passes and over which is threaded a series of nuts 25. Another wire 26 communicates with a suitable source of electric current, not shown, for conducting the current to the armature and commutator terminals for the purpose of welding the respective members together.

An axially movable arm 27, comprising a part of the hub 28, is slidable upon the sleeve 14, being resiliently moved toward the 90 armature by a relatively strong spring 29. A handle 30 is employed for moving the arm in the opposite direction, against the effect of the yielding spring. The inner upper face of the arm 27 is provided with a contact shoe 31 for engagement with the ends of each of the commutator segments 18, when brought into connection therewith, for the purpose of welding the segments, or sections, to the terminals 9 of the armature conductors. A wire 32 leads to the same source of current as the wire 26 for conducting the current to the welding apparatus.

The insulating ring 16 is provided with 105 as many radially extended pockets as there are commutator segments 18. These pockets are contained between adjacent separating plates 17. After the armature ends 9 have been arranged in proper concentric relation with their end faces in a vertical plane perpendicular to the axis, the segments 18, are 110 one at a time, placed in the pockets between

the separators 17, and the shoe 31 of the arm 27 is brought into contact with the outer surface of the commutator segment 18. The tension of the spring 29 will produce sufficient pressure to move the arm 27 inwardly, thereby pressing the inner surface of the commutator section into contact with the surface of the respective pairs of terminals, as they are joined together at 9, thereby causing a weld. After a weld between one commutator segment and its paired terminals has been completed, the arm 27 is moved back and slightly rotated and another segment is placed in a pocket between the separators 17 and the process repeated until the entire number of segments have thus been butt-welded to the ends of the terminals 9. After this has been accomplished the armature may be removed from the welding apparatus, the ring 20 having been loosened permits the commutator and the terminals 9 to slip back over the ends of the disc 13 and carries the ring 20 with it, after which the ring may be removed from the finished commutator.

In Fig. 3 I have shown a brush holder 33 carrying a brush 34, spring pressed by spring 35 and engaging the outer surface of the commutator. I have also shown a brush

holder 36 carrying a brush 37 and spring 38 pressed by spring 39 and bearing upon the inner surface of the commutator. Either set of brushes may be used in connection with the commutator, or both may be used, one on the outer surface of the commutator and one set on the inner surface of the commutator, in order to increase the current carrying capacity of the commutator.

Having described my invention, what I claim is:—

In combination with an armature having a series of paired conductors projecting from the end of the core, the ends of all of the conductors terminating in substantially the same diametric plane; a divided commutator ring having a collecting surface outside and inside of the ring, each cylindrical surface to receive collecting brushes, there being a segment of the ring for each pair of conductors, and each segment joined at one of its sides between the inner and outer annular surfaces to a pair of conductors to render both said annular surfaces available for commutating purposes.

In testimony whereof I hereunto set my hand.

VINCENT G. APPLE.
